UNITED STATES PATENT OFFICE

JOHN H. DUNN, OF BURLINGTON, IOWA

MUSIC-LEAF TURNER

Application filed August 11, 1928. Serial No. 299,026.

The invention has relation to music leaf turners, having for an object the provision of an improved device of this description.

The invention consists in the novel construction and combinations of parts as set forth in the appended claims.

In the accompanying drawings illustrating the invention Figure 1 is a front view of the invention with the front cover of the lower horizontal hollow bar or box removed; Figure 2 is a side view of the invention partly in section; Figure 3 is a rear view of the mechanism contained in the lower horizontal bar or box, and Figure 4 is a plan view of the same.

In these drawings the numeral 1 designates the music rack, adapted to be supported upon a piano, a music stand, or other place and having a hollow upright center bar 2, where-
20 in a rotatable sleeve 3 has bearings, said sleeve carrying at its upper end a radial arm 4, having at its free end depending spaced fingers 5 adapted to be engaged with a sheet of music to be turned, the lower end of said sleeve car-
25 rying fast thereto a small gear wheel or pinion 6. Rotatably mounted within the sleeve 3 is a concentric sleeve 7, the latter carrying at its upper end fast thereto a radial arm 8 located above and spaced from and somewhat
30 longer than the radial arm 4, arm 8 having also depending spaced fingers 9 for engage-
ment with a sheet of music to be turned. The lower end of the inner concentric sleeve 7 is provided with a small gear wheel or pinion
35 10, located below and spaced from the pinion 6. Rotatably mounted within the sleeve 7 is a rod 11, concentric with the sleeves 4 and 7, said rod carrying at its upper end fast thereto a radial arm 12 located above and
40 spaced from and somewhat longer than the radial arm 8, the arm 12 having also depend-
ing fingers, designated 13, which are adapted to be engaged with a sheet of music to be turned. The rod 11 has at its lower end a
45 fast gear wheel or pinion 14 located above and spaced from the pinion 10, the three pinions being in line.

The music rack is provided with a lower horizontal hollow bar or box 15, wherein the three said pinions are located centrally there-

of. 16 is a base plate forming the bottom of said hollow bar or box 15 and carrying uprights 17 within slots of which reciprocating bars 18 have movement. Each of said bars 18 is provided with a notch 19 in its upper 55 surface, a rack 20, and a retraction spring 21. These reciprocating bars are located one above another in upright series and the racks thereof are engaged by the pinions 6, 10 and 14 aforesaid, whereby movement of said bars 60 will cause movement of said pinions and rotate the radial arms 4, 8, and 12 through 180° or a half circle. Movement of any one of said bars in one direction will cause rotation of the related radial arm to the extent stated. 65

In the use of the invention, the radial arms are first set to the right, which may be accomplished by moving all of the reciprocating bars 18, to the left, this being done by the use of setting devices consisting of parallel 70 spaced horizontal push rods 22, working in slots of uprights 23 of the base plate, each push rod having an operating projection 24 and a retraction spring 25, and relating to one of the reciprocating bars 18. These bars 75 being set to the left are caught and held with the retraction springs thereof under tension, by pawls 26, one for each bar, said pawls being pivoted at 27 and having offset teeth 28, each engaged with the notch of the related 80 bar 18, a spring 29 serving to hold the pawl depressed with its tooth engaged with the notch of the bar.

The radial arms 4, 8, and 12 being then set to the right and the depending fingers 85 thereof engaged with the sheets of music to be turned, it remains to move the radial arms one at a time through an arm of 180° to first position in order to turn the sheets of music, this being done by means of horizontally 90 spaced depressible vertical pins or keys 30, of which there are three, one for each radial arm to be turned, these keys being in horizontal series, engaging perforations of the top of the horizontal box 15 and at their lower 95 ends engaging respectively with levers 31, of which there are three, one for each pawl 26, said levers being fulcrumed at 32 and having their work arms engaged under the teeth of the pawls 26, and their power arms of dif- 100

ferent lengths so that the horizontal series of depressible releasing keys 30 will engage each one of said levers and separately depress the same to release the related bar 18, whereupon its retraction spring will operate to shoot the bar home to normal position, and thereby flip the related radial arm and turn the sheet of music engaged thereby.

In order that all of the bars 18, the concentric rod and sleeves, radial arms and depending fingers for turning the sheets of music may be set simultaneously by a single operation, the middle of the reciprocatory bars, which are parallel and horizontal, is provided with rear projections 33, one of which extends downwardly in rear of the lower bar 18, and the other upwardly in rear of the upper bar 18, so that when the upper bar 18 is moved to set position by its push rod device, a rear projection 34 thereof will engage upper projection 33 of the middle bar and move said bar therewith, the lower projection 33 of the middle bar in turn engaging a rear projection 35 of the lower bar and moving the latter therewith, the three holding pawls 26 engaging the upper notches of the bars simultaneously.

The depressible keys 30 for turning the sheets of music are operated from left to right, one at a time, and each of said keys is raised above the others by the raising of the levers 31 (power arms thereof) when the other or work arms of the levers are depressed by engagement of the teeth of the pawls 26 with the notches of the bars 18. If there is but one sheet of music to be turned, only one key 30 will be raised, being the endmost key or pin to the right, if two sheets are to be turned, two keys 30 will be raised, and if three sheets are to be turned, three keys 30 will be raised, these keys being when not raised, incapable of operation owing to being flush at the tops thereof with the top of the box 15.

Any music sheet of the three engaged by the radial arm fingers of the concentric rod and sleeves may be returned to normal or first position after being turned, in case a repetition is wanted, by moving the proper one of the operating projections 24. The setting means, the releasing means, the reciprocatory bars and the gear wheels for the rotation of the concentric rod and sleeves 3, 7, and 11, to turn the music sheets, are all compactly arranged and located within said hollow bar or box 15 and thereby protected. Such operating mechanism is all attached to the base plate 16 of said box and may be inserted in position and removed as a unit.

At the upper end of the upright center bar 2 of the music rack, is a flat plate extension 36 in line with said bar and to which are secured two spaced depending clamping tongues 37, 37', cooperating with the flat surface of said plate to hold the right hand and

the left hand portion of a small lightweight music book with the middle leaves thereof free in order that they may be readily turned.

In case a piece of music has but one sheet to be turned the back cover sheet is engaged under spring tongue 37' only, which is longer than tongue 37, with the hinge or fold at the left of spring tongue 37', the lower part of the back cover sheet being engaged by lower spring tongue 38, which is capable of being turned forward pivotally if desired previous to clamping engagement with the sheet of music. This being done, the loose sheet is then engaged with the spaced fingers 13 of the longest radial arm 12, the latter being then set to the right by operation of the related setting projection 24, which is the lowermost of the three setting projections. The related depressible key 30, which is the endmost to the right will be raised above the others and above the top surface of hollow box 15 in the setting, and upon depression of the same the sheet of music will be flipped over to the left.

In the case of a piece of music having two sheets to be turned, proceed as above, engaging one of the sheets to be turned with the spaced fingers 13 of the longest radial arm 12, and the other with the spaced fingers of the middle radial arm both of these radial arms being then set to the right by operation of the related setting projections 24, being the two lowermost although as explained movement of the middle setting projection 24 will move the lower one therewith. The related of the depressible keys 30, which are the two endmost to the right will be raised above the others, and upon depression of the same, beginning with the one to the left, the sheets of music will be flipped over to the left seriatim. It will be noted that it is not possible to readily depress the wrong key 30 and flip the wrong sheet.

In case of a piece of music having three sheets to be turned, proceed as before, but engaging both spring tongues 37, 37', with the music, one at each side of the fold or hinge, engaging the first sheet to be turned with the spaced fingers of the longest of the radial arms, the middle sheet to be turned with the spaced fingers of the middle radial arm, and the third sheet to be turned with the spaced fingers of the shortest radial arm, the three radial arms being then set to the right by operation of the related setting projections 24, beginning with the lowest projection, if the setting is to be separately accomplished, which is easier, as only one retraction spring is then tensioned at a time, or using the uppermost projection 24, if all three are to be set at the same time. The depressible keys 30, of which all three are raised in the setting, are then depressed in order as required, beginning with the endmost to the left.

It will be noted that while the showing applies to music having only three sheets to be turned, after which a new insertion of sheets to be turned is needed, yet the device may readily be adapted to turn more than three sheets of music without a new insertion of sheets to be turned by a further duplication of the parts, as will be obvious.

In the case of a music book of bulky character, having many leaves, the upper and lower spring tongues 37, 37' and 38 are disregarded, and the book is inserted in the device behind the spaced fingers of the radial arms and resting upon lower out-turned brackets 39, of which there are two, one at each side of the music rack. This being done, one, two or three leaves to be turned are then engaged as stated previously with the spaced fingers of the radial arm or arms, said arms or

20 arms are set, and the turning accomplished by depression of the depressible key or keys.

The music is readily inserted in position and readily removed, and it is not necessary to have the fold or hinge exactly in the center 25 of the rack.

The rear portion or back of the music rack is provided with props 40, one at each side, to support the rack at a suitable incline, and with a center piece 41, for engagement with 30 a music stand support.

Means are provided to prevent the depression of the wrong key 30 and turning of the wrong sheet of the music, this being the same means provided to enable all of the bars 18, 35 the concentric rod and sleeves, radial arms, and depending fingers to be set simultaneously by a single operation, namely the upper and lower rear projections 33 of the middle bar 18, rear projection 34 of the upper bar 40 18, and rear projection 35 of the lower bar 18.

I claim:—

1. In a music leaf turner, a plurality of concentric rotatable shafts carrying at one end each a radial arm having fingers for turning 45 the music leaves and at the other end each a gear wheel, a plurality of parallel spring retracted reciprocatory bars carrying each a rack engaging one of said gear wheels, means for independently setting said shafts and 50 fingers including a spring catch for holding each bar as set and a spring retracted pusher device for each bar, independent releasing means including a lever for raising each catch and a depressible key for operating each 55 lever, and means for normally concealing said keys from view adapted to cause the keys to be independently exposed to view in the setting operation.

2. In a music leaf turner, a music rack having 60 a central upright hollow bar and a lower horizontal hollow bar, a plurality of concentric rotatable shafts located within said upright hollow bar and carrying each at one end a radial arm having fingers, and at the other end each a gear wheel, a plurality of

parallel spring retracted reciprocatory bars carrying each a rack engaging one of said gear wheels, means for independently setting said shafts and fingers including a spring catch for holding each reciprocatory bar as set and a spring retracted pusher device for each bar, and independent releasing means including a lever for raising each catch and a depressible key for operating each lever, said gear wheels, reciprocatory bars, setting means and releasing means being all compactly arranged within said lower horizontal bar, said keys projecting upwardly within horizontally aligned perforations of the top of said lower horizontal bar.

3. In a music leaf turner, a plurality of concentric rotatable shafts carrying at one end each a radial arm having fingers for turning the music leaves and at the other end each a gear wheel, a plurality of parallel spring retracted reciprocatory bars carrying each a rack engaging one of said gear wheels, means for independently setting said shafts and fingers including a spring catch for holding each bar as set and a spring retracted pusher device for each bar, and independent releasing means including a lever for each catch and a depressible key for each lever, and a frame member having perforations within which said keys are normally depressed and concealed and above which each key is independently raised into view in the setting operation.

4. In a music leaf turner, a music rack having a central upright hollow bar and a lower horizontal hollow bar, a plurality of concentric rotatable shafts located within said upright hollow bar and carrying each at one end a radial arm having fingers and at the other end each a gear wheel, a plurality of parallel spring retracted reciprocatory bars carrying each a rack engaging one of said gear wheels, means for independently setting said shafts and fingers, and independent releasing means including a depressible key for each reciprocatory bar, the setting means and the releasing means, the reciprocatory bars and the gear wheels, being all compactly arranged within said lower horizontal bar, the top of the latter having a horizontally aligned series of perforations and said keys being normally depressed within the same and each raised above the top of the same in the setting operation.

In testimony whereof I affix my signature.
JOHN H. DUNN.
